206,308

SAUNA HEATER

Ben Steinman, 52 Edgerwood Lane,
Huntington, N.Y. 11743

Filed Nov. 22, 1965, Ser. No. 88,180

Term of patent 14 years

(Cl. D81—20)

FIG. 1 is an isometric view of a sauna heater showing the top, front and one side of my new design; and

FIG. 2 is an isometric view of the sauna heater of FIG. 1 showing the top, rear and other side thereof.

I claim:

The ornamental design for a sauna heater, substantially as shown.
